G. WRIGHT.
SHADE MOUNTING.
APPLICATION FILED MAY 5, 1915.

1,192,722.

Patented July 25, 1916.

Inventor:
Gilbert Wright,
Alfred J. Damm
His Attorney.

UNITED STATES PATENT OFFICE.

GILBERT WRIGHT, OF SCHENECTADY, NEW YORK, ASSIGNOR TO GENERAL ELECTRIC COMPANY, A CORPORATION OF NEW YORK.

SHADE-MOUNTING.

1,192,722.

Specification of Letters Patent. Patented July 25, 1916.

Application filed May 5, 1915. Serial No. 25,910.

To all whom it may concern:

Be it known that I, GILBERT WRIGHT, a citizen of the United States, residing at Schenectady, in the county of Schenectady, State of New York, have invented certain new and useful Improvements in Shade-Mountings, of which the following is a specification.

My invention relates to shade mountings and the like, and it is concerned with the mounting of reflectors, shades, globes, and other inclosures used with incandescent lamps and the like, and more particularly with the attachment of holders for such inclosures to sockets and receptacles for such lamps.

It is my aim to make the mounting simple, secure, convenient, and reliable in use, and easy and inexpensive to manufacture.

While the specific embodiment of the invention herein illustrated and described is the best at present known to me, and while the invention extends to specific features and details as illustrated, yet the invention is not confined to such details, but can be otherwise carried out and embodied.

The accompanying drawing is an elevation of a lamp socket with a shade holder mounted and secured thereon in accordance with my invention, portions of the shade and the shade-holder being broken away and removed.

It will be seen that the socket 1 shown comprises a sheet metal cap 2 and a sheet metal shell 3 of ordinary general form, these parts being secured together in any approved manner. The interior parts of the socket 1 are not shown because the invention is not concerned with them; they may be of any usual or preferred construction. The upper portion of the socket 1 is enlarged as usual as compared to the lower portion, these portions of different diameter being united by a rounded shoulder 4. It will be observed, however, that the shell 3 differs from those in common use in that its lower portion is not annularly enlarged or beaded near the lamp receiving end, but instead has a screw thread 5 of about two turns rolled in the portion that would ordinarily form the bead. This thread 5 is shown as formed entirely by forcing the metal outward. The aggregate width of the screw thread 5 is about equal to that of the usual bead, so that shade holders and the like intended for

ordinary beaded sockets can also be secured to this threaded socket 1 in the usual manner.

The shade-holder 6 shown in the drawing comprises inner and outer shade-engaging members 7 and 8 which are correlative screw-threaded so that they may be screwed together to grip the shade 9, which is itself shown as a glass reflector with its neck portion 10 of the beaded and groove form usual in such articles. The inner member 7, it will be seen, is expanded and flared at its lower end so as to fit within the shade neck 10, while the outer member 8 is expanded so as to overlie the shade neck, and also flared so as to extend down over the bead and groove. As shown, the correlative screw-threads of the members 7 and 8 are on upwardly extending sleeve portions or necks 11 and 12 of said members. When the members 7 and 8 are screwed together so as to grip the shade neck 10, their flange portions 13 and 14 may abut as shown.

It will be seen that the shade-holder 6 is internally threaded so as to screw on the externally threaded lower portion of the socket 1, and that the sleeve or neck portion of one of its members incloses said lower portion of the socket and abuts against its enlarged upper portion at the shoulder 4; as shown, the socket-engaging threads are inside the neck 11 of the inner member 7, and it is the neck 12 of the outer member 8 that abuts at the shoulder 4.

It will further be seen that the external and internal threads of the neck 11 of the inner member 7 are formed by helically corrugating said neck (as by a rolling operation), and that the internal threads of the neck 12 of the outer member 8 are similarly formed, but in such a way as to make the threaded portion of slightly less general diameter than the rest of the neck 12. The upper edge of the neck 12 is slightly rounded or beaded inward to improve the appearance of the shade-holder 6 when in place on the socket 1. Preferably the members 7 and 8 are made of fairly thin and resilient sheet metal.

It will be observed that besides being easy to secure to the shade 9 and easy to attach to the socket 1 when so secured, the shade-holder 6 presents a very good appearance when in place, and that its parts can be easily and rapidly produced by simple dies and by spinning and rolling operations.

When the holder 6 is being screwed on the socket 1, the tendency is to tighten its grip on the shade 9, and the harder it is screwed against the shoulder 4 the tighter the grip becomes.

What I claim as new and desire to secure by Letters Patent of the United States, is:—

1. A shade-holder comprising a shade-engaging member with an upwardly extending internally screw-threaded neck and another shade-engaging member having a neck externally screw-threaded so that it may screw into said first-mentioned member for the purpose of securing a shade in the holder, and internally screw-threaded so that it may screw on a socket.
2. A shade-holder comprising a shade-engaging member adapted to overlie a shade neck and itself having an upwardly extending internally screw-threaded neck, and another shade-engaging member adapted to fit within the shade neck and itself having an upwardly extending neck helically corrugated so as both to screw into said first-mentioned member for the purpose of securing the shade in the holder and to screw on a socket.
3. A shade-holder for a socket with an externally screw-threaded lower portion and an enlarged upper portion, said shade-holder comprising a shade-engaging member adapted to overlie a shade neck and having an internally screw-threaded portion, and another shade-engaging member adapted to fit within the shade neck and having a portion externally screw-threaded so that it may screw into said first-mentioned member for the

purpose of securing a shade in the holder, and internally screw-threaded so that it may screw upon a socket, the screw-threaded portion of one of said members being in the form of an upwardly extending neck adapted to inclose the lower portion of the socket and abut against its enlarged upper portion.

4. A shade-holder for a socket with an externally screw-threaded lower portion and an enlarged upper portion, said shade-holder comprising a shade-engaging member adapted to overlie a shade neck and itself having an upwardly extending internally screw-threaded neck, and another shade-engaging member adapted to fit within the shade neck and having an upwardly extending neck helically corrugated so as both to screw into the neck of said first-mentioned member for the purpose of securing the shade in the holder and to screw on the lower portion of the socket, the neck of said first-mentioned member being adapted to inclose the lower portion of the socket and abut against its enlarged upper portion.

5. A shade-holder for a socket with an externally screw-threaded lower portion and an enlarged upper portion, said shade-holder being internally screw-threaded so as to screw on said lower portion of the socket and comprising a member having a shade-engaging portion and an upwardly extending neck adapted to inclose said lower portion of said socket and abut against said enlarged upper portion.

In witness whereof I have hereunto set my hand this 30th day of April, 1915.

GILBERT WRIGHT.
